OUTBOARD MOTOR ASSEMBLY

Louis J. Johnson, South Bend, Ind., and Harry L. Johnson, Waukegan, Ill., assignors to Johnson Brothers Engineering Corporation, South Bend, Ind., a Corporation of Indiana

Application January 28, 1929. Serial No. 335,446

4 Claims. (Cl. 123—190)

Our invention relates to an outboard motor assembly and more particularly to a rotary valve construction for outboard motors and the like.

One of the primary objects of our invention is to provide, in combination with an internal combustion engine such as an outboard motor, means whereby the quantity of explosive mixture directed to the cylinders may be appreciably increased and to this end we propose to provide a valve of simple and durable construction through which the explosive mixture may pass as it is directed from the carburetor to the crank case, the actuation of said valve being timed in accordance with the rotation of the crank shaft.

More specifically, our invention contemplates the provision of a valve in association with outboard motors and the like which is of a rotary type, said valve being positively actuated in response to the rotation of the crank shaft so as to permit the explosive mixture to be introduced within the crank case of the motor during a predetermined interval.

A still further object of our invention is to provide a rotary valve construction, as set forth above, which is not only positively driven in response to the rotation of the motor crank shaft but which is provided with simple and effective means whereby the timing of said valve, with respect to the angular displacement of the crank shaft, may be varied.

Another object of our invention is to provide a rotary valve construction which is particularly adaptable for outboard motor assemblies, and which is so designed as to permit the introduction of explosive mixture axially of the valve and the discharge of explosive mixture into the motor crank case laterally of the valve.

A still further object of our invention is to so arrange the timing of the admission of the charge from the rotary valve to the crank case, that at the time of entrance of the said charge the lower crank pin of the two horizontal posed cylinders is passing the entering orifice, tending to force the greater part of the charge to the upper half of the crank case space, which in turn tends to supply the greater portion of the gas to a point in the crank case adjacent the higher cylinder of the offset cylinders, thus gaining a perfect distribution by offsetting the tendency of the lower cylinder to receive a greater charge of gas than the higher one.

In addition to the above mentioned advantageous characteristics, our invention contemplates the provision of an outboard motor having a rotary valve construction which has a geared

connection with the motor crank shaft, said geared connection being completely housed within the crank shaft housing so as to insure the lubrication thereof, said geared connection being further adjustably arranged to readily permit the valve to be timed in accordance with the rotation of the motor crank shaft.

These and other objects will be more apparent from the following detailed description when considered in connection with the accompanying drawings, wherein—

Figure 1 is a side elevational view of the upper portion of an outboard motor assembly which is equipped with a rotary valve structure embodying features of our invention;

Figure 2 is a fragmentary horizontal sectional view taken substantially along the line 2—2 of Figure 3 disclosing in plan the adjustable valve actuating gears;

Figure 3 is an enlarged central vertical sectional view of a portion of the motor assembly shown in Figure 1;

Figure 4 is a detailed horizontal sectional view taken substantially along the line 4—4 of Figure 3 to more clearly disclose the structure of the rotary valve; and

Figure 5 is a detailed elevational view of the engine head as viewed from the right of Figure 3, a portion of the crank case and cylindrical head being broken away to disclose parts otherwise hidden.

Referring now to the drawings more in detail, it will be observed that for the purpose of illustrating a practical embodiment of our invention, an outboard motor assembly designated generally by the numeral 10 is disclosed in Figures 1 and 3. This motor 10 includes a vertical type crank shaft 12, the lower extremity of which is operatively connected with a vertical drive shaft 14 and the upper extremity of which supports a fly-wheel 16, Figure 3. The motor 10 is of the opposed cylinder construction, cylinders 18 and 18^a, Figure 1, being disposed on opposite sides of a crank case 20. Suitably secured to the forward side of the crank case 20 (to the left, Figures 1 and 3) is a rotary valve assembly which is designated generally by the numeral 22. This rotary valve assembly 22 comprises a casing 24 which is vertically bored to receive a rotary valve 26. This valve 26 is supported by a shoulder 28 provided on a vertical shaft 30, and the upper and lower extremities of this shaft 30 are provided with suitable roller bearing mountings 32 and 34 respectively. The

valve 26 is provided with a recess or passageway 36 which is designed to establish communication between the chamber 38 within the crank case 20 and a passageway 40 at the lower end of the 5 casing 24 when said valve is positioned as shown in Figure 3. The lower end or entrance of the recess 36 is circular and converges upwardly and laterally (to the right, Figure 3) and terminates in a rectangular opening designated by the 10 numeral 42. This rectangular opening or exit 42 is adapted to be rotated past and to register with a greater opening 44 provided in the casing 24, and when these openings register with each other, communication will be established between 15 the chamber 38 and the passage-way 40. This passage-way 40 is connected, by means of suitable pipe connections, with a carburetor 46, Figure 1, and from the foregoing it will be apparent that explosive mixture from the carburetor 46 may pass freely into the chamber 38 when the rotary valve 26 is positioned as shown in Figure 3.

Rotation is imparted to the rotary valve 26 through the agency of a pair of gears 48 and 25 50. The gear 50 is secured to the crank shaft 12 and meshes with the gear 48 which is adapted to be operatively connected to the valve 26 by means of a pin 52, Figures 2 and 3. This pin 30 52, which is inserted at its lower extremity within the rotary valve 26, extends upwardly from said valve a sufficient distance so as to permit one of three concentrically arranged apertures 35 54, provided in the gear 48, to be operatively associated therewith. Referring now particularly to Figure 2, it will be seen that these apertures 54 are angularly spaced so as to permit the opening and closing of the valve 26 to be advanced or retarded. This will be more readily appreciated when the gear 50 is considered as bearing 40 a fixed relation with respect to the crank shaft 12 and consequently with respect to the position of the pistons (not shown) which reciprocate within the cylinders 18. The gear 48, however, may be lifted upwardly from its seat upon the valve 26 sufficiently to disengage one 45 of the apertures 54 from the pin 52 and then freely rotated independently of the rotary valve. Thus, if the gear 48 is disengaged from the pin 52, Figure 2, and rotated in the direction of its 50 normal rotation, as indicated by the arrow, until the next following aperture registers with the pin 52, the gear 48 will not mesh with the gear 50 until said gear 48 and the valve now connected therewith, is rotated through an angular distance equivalent to one-third of the width of the gear tooth. In other words, by angularly shifting the gear 48 until the next following aperture 55 54 registers with the pin 52 and then imparting an additional rotation to the connected parts, the timing of the valve is slightly advanced. Obviously, if it is desired to rotate the valve for the purpose of advancing it through a distance equivalent to two-thirds of the thickness of the gear teeth, it is only necessary to cause the second following aperture 54 to be carried into registration with the pin 52. It will be apparent that if it is desired to shift the valve through a distance equivalent to a tooth thickness, it will not be necessary to disengage the gear 48 from the valve 26. In that instance it will only be necessary to disengage the gear 48 from the gear 50 and then move the gear 48 in the direction indicated through a distance equivalent to the thickness of one tooth. By employing the angularly spaced apertures 54, a very

refined and accurate timing adjustment of the valve 26 may be made and this feature is decidedly advantageous in connection with the operation of internal combustion engines such as the disclosed outboard motor 10. From the foregoing it will be readily understood that in order to retard the valve 26, it will only be necessary to move the gear 48, with respect to the gear 50, in a direction opposite to that indicated by the arrow in Figure 2. In other words, the gear 48 would be disengaged from the pin 52, moved in a clockwise direction until the next following or the second following aperture is carried into registration with the pin 52. A cap 56 is adapted to be secured to the upper portion of the casing 24 by means of bolts 58, and from the foregoing it will be apparent that when this cap is secured in position, both of the gears 48 and 50 will be completely housed or shielded within their respective casings and the lubrication thereof is therefore positively insured. Oil from the crank case 20 will also serve to effectively lubricate all of the other movable parts which have been described in connection with the consideration of the rotary valve assembly 22. A 100 protecting cap 60 is also provided at the lower end of the casing 24 as clearly shown in Figures 1 and 3.

Attention is directed to the fact that in the particular embodiment of the motor shown in the drawings, the cylinder 18 is vertically offset with respect to the cylinder 18^a. When the rotary valve just described is employed in connection with an outboard motor having these offset opposed cylinders it is desirable to have the valve 105 open during the period when the portion of the connection rod 59 of the lower cylinder which is coupled with the crank shaft is swept immediately in front of the valve as clearly shown in Figure 3. When the lower connecting rod 59 is 110 being swung through the above mentioned path, the upper connecting rod 61 is being moved so that the end coupled with the crank shaft is remotely positioned with respect to the rotary valve. The introduction of the fuel or gas into the crank 115 case when the connecting rods occupy the above mentioned relation insures a much more uniform distribution of the fuel into the cylinders than would result if the upper rather than the lower crank shaft were swung in front of the valve as 120 said valve was opened. If the later relation were employed the fuel, which normally seeks a lower level, would more readily flow into the lowermost cylinder 18^a than into the higher cylinder 18, thereby establishing non-uniform distribution of 125 the fuel into said cylinders. By having the rotary valve opened at the bottom as indicated in the drawings, that is, at the period when the lower crank shaft is moved adjacently with respect to the rotary valve, we have been able to 130 obtain the desired uniformity in distribution of the fuel to the cylinders.

From the foregoing description it will be understood that our invention contemplates the provision of a rotary type inlet valve of simple and 140 economical construction which will serve to establish communication between the carburetor and the engine crank case chamber at proper predetermined intervals. The opening of the rotary valve may be so timed as to permit of the 145 introduction of the explosive mixture into the chamber 38 when the pistons (not shown) occupy a predetermined position within their respective cylinders 18. Thus the valve may be so timed as to allow the explosive mixture to be taken into 150

the crank case during the complete compression stroke of the cylinder and to close during the expanding stroke thereof. In this way an increased charge of explosive mixture may be introduced within the cylinder. In other words, the closing of the valve 26 during the power stroke of the piston prevents any of the mixture within the crank case from being forced back into the passages leading to the carburetor. Our invention provides a very unique and simple means for accurately timing the valve and this timing may be made within refined limits. By having the movable or rotative parts constituting the rotary valve assembly completely housed, the lubrication of such parts is insured and the possibility of foreign matter being introduced is positively precluded. By constructing the valve 26 so that the gases are taken in axially of the valve and discharged laterally thereof, a very positive flow of said gases from the passageway 40 into the crank case chamber 38 is insured by reason of the centrifugal force within the valve recess which tends to force said gases laterally into the chamber 38. The rotary valve 26 is very light in construction and in fact, to increase its lightness, a cavity 62 is provided, as clearly shown in Figures 3 and 4. When the rotary valve is employed with engine heads having opposed offset cylinders we are able to obtain the desired uniformity in distribution of the fuel to the cylinders by effecting the opening of the valve during the time when the lower connecting rod and crank shaft arm are being swung past said valve as already described.

Our improved rotary valve unit is particularly adaptable for use with outboard motors of the horizontally rotatable and vertically tiltable type. The compactness of the unit and the positive gear driving mechanism protectively housed within the unit enable the same to be conveniently attached to the side of the motor crank case. By having the timing gear supported at the upper end of the valve and covered by the removable cap, a very convenient and practical construction is afforded and access to all of the movable parts within the unit may be readily effected.

Having thus described our invention, what we claim as new and desire to secure by Letters Patent is:

1. In combination with a chamber of an internal combustion engine, a rotary valve unit including a closed casing independently secured to the wall of said chamber and communicating therewith, said casing provided with a bore, a cylindrical valve rotatable within said bore, a shaft extending axially of and supporting the cylindrical valve, a gear connected to said cylindrical valve and extending through the valve opening into the chamber, a separate removable member for protectively covering and enclosing said gear,

and means connecting said gear with a movable element of the engine.

2. In combination with the crankcase of an internal combustion motor, a rotary valve unit including a casing adapted to be removably secured to and communicating with the interior of the crankcase of the motor, a vertical bore within the casing, a cylindrical valve rotatable within said bore, a vertical shaft extending axially of and supporting said cylindrical valve, a passageway within said valve adapted to establish communication between the motor crankcase and the carburetor in response to rotation of the cylindrical valve, a gear secured to and seated upon the upper end of the valve and extending through the valve opening, a removable cover member positioned immediately above said gear, and a second gear secured to the crank shaft of the motor and operatively connected with the gear on the cylindrical valve, the gears being enclosed by the crank case and valve casing.

3. In combination with the closed crank case of an internal combustion motor having a drive shaft, a rotary valve unit including a casing adapted to be removably secured to and communicating with the interior of the crank case of the motor, a cylindrical valve rotatable within said casing, said valve having a passageway for establishing communication between the motor crank case and the carburetor system, one end of said passageway being concentrically arranged with respect to the valve and the other end thereof terminating peripherally of the valve so as to permit the discharge of gases laterally thereof into the motor crank case, a shaft positioned axially of and supporting the cylindrical valve, said shaft being rotatable within the casing, a gear adjustably secured to the upper end of the cylindrical valve, and another gear carried by the drive shaft of the motor, said gear meshing with the gear carried by the cylindrical valve, and the gears being connected through the same opening in the crank case as that for the valve and enclosed by the motor crank case and the valve casing, and the valve gear being accessible for renewal and adjustment independent of the motor gear.

4. The combination with a combustion engine having a closed crank case and a crank therein with an attached driving gear, of an attached rotary valve unit having a valve member, an attached gear, and a casing therefor; the casing having an opening communicating with an opening in the crank case, and the gears being connected through the same opening which forms communication for the valve.

LOUIS J. JOHNSON.
